DOUBLE-ACTION DOOR CLOSING DEVICE

Herman H. Pancake, Glen Rock, N. J., assignor
to American Car and Foundry Company, New
York, N. Y., a corporation of New Jersey

Application January 21, 1949, Serial No. 71,870

9 Claims. (Cl. 214—63)

1

This invention relates to door closing devices in general and in particular to such devices used in conjunction with drop bottom mine and industrial cars.

Door closing devices similar to that shown in my Patent 2,374,155 have been used extensively, but these devices fail to operate properly when cars having mixed sized wheels are used over the same closing device. Also, occasionally an operator will purchase a locomotive having excessively low clearances and such locomotives can not pass over the closing ramp. It is an object, therefore, of the present invention to provide a ramp which has a high lift permitting closing of doors on cars having different diameter wheels.

A further object of the invention is the provision of a door closing ramp having a high lift to close the doors of the cars having varying clearances with respect to the rail top.

A yet further object of the invention is the provision of a door closing device combining rockers and rollers to produce a double action closing device of high lift.

These and other objects of the invention will be apparent to persons skilled in the art from a study of the following description and accompanying drawings, in which

Fig. 1 is a sectional view taken through a car and showing the same with doors closed and returning over the ramp;

Fig. 2 is a bottom view of the device with parts broken away to better disclose the construction;

Fig. 3 is a sectional view taken substantially on line 3—3 of Fig. 1, and

Fig. 4 is a sectional view through the car with parts of the closing device broken away and showing the parts in raised or door closing position.

Referring now to the drawings in detail, it will be seen that the car is of more or less conventional form having side sills 2 supported on axles 4, which in turn are supported by wheels W adapted to roll on rails R, the top surface only of which is indicated. The doors D are mounted to swing on hinges 6 between open and closed positions and when in closed position are held by the next rearward door as clearly shown in Fig. 1.

The door closing device includes a base member 8 of more or less channel cross-section formed by angle members with outturned flanges 10 by means of which it may be attached to any suitable supporting structure and the upstanding flanges are connected by a plate 12 welded in position between the angle form members and having parts 14 thereof inclined upwardly and forwardly to provide sloping trackways within the base member. These trackways are preferably provided with tapered holes 16. It is obvious, of course, that this base member may be shaped differently or that the sloping trackways may be formed merely as part of the rigid structure at the dumping pit of the mine.

Mounted on the sloping trackways 14 are rockers 18 of substantially cylindrical curvature and

2

with portions of the curved surface provided with lugs 20 adapted to engage with tapered holes 16, thereby preventing any slippage between the rockers and the sloping trackways. In order to

5 prevent the rockers from being lifted completely out of the base member, a pin or bolt 22 extends through each rocker and through slots 24 formed in the upstanding walls of the base member. The upper portion of the rockers is hollowed out as 10 at 26, Figs. 3 and 4, in order to accommodate a roller 28, which roller is journaled on an axle pin or bolt 30 extending through the rocker substantially at the center of curvature of the rocker surface. The pins or axles 30 also extend outwardly 15 beyond the rockers and through slots 32 formed in the downturned flanges 34 of the door engaging ramp member. In order to provide greater wearing surface and reinforcement plates 36 may be slotted and welded to the downturned members 34 with their slots in alignment with the 20 slots 32. Lubricant may be fed to the rollers 28 by means of fittings 38 fastened in the end of axles 30 and joining up with passages extending into the roller 28.

25 The door engaging ramp member is preferably formed with a substantially flat top plate 40 having its rearward edge curved downwardly a considerable amount as at 42 and the entire side edges of this plate are welded or otherwise secured

30 to the downturned sides 34 previously referred to. It is obvious, of course, that this member may be formed of a channel without welding, although it is generally cheaper and more satisfactory to weld the parts as shown. Within the downturned

35 channel form ramp member are welded trackways 44 which incline downwardly and rearwardly as best shown in Figs. 1 and 4. These trackways may, of course, if desired be pressed into the top surface member 40 instead of welded thereto as 40 shown, or the entire ramp member with its trackways may be cast or otherwise formed. The trackways 44 rest upon the rollers 28 and support the weight of the ramp member so that the axles 30 do not normally rub on the edges of slots 32.

45 When the ramp is in its normal lowered position as shown in Fig. 1, the top surface 40 is substantially flush with the top of the rail indicated at R and accordingly any locomotive or car can operate thereover without damage to the locomotive.

50 When a car with doors open, however, is moving forwardly as indicated by the arrow T of Fig. 4, the hanging doors will strike the down-curved rearward edge 42 of the door engaging ramp and move the same longitudinally forward, that is, forward with respect to the travel of the car during closing. Movement of the door engaging ramp forwardly by the hanging doors will

55 cause the rockers 18 to rock along their tracks 14, thereby raising the axle 30 which extends 60 through the rockers adjacent to the center of curvature of the rockers. Simultaneously with this rocking movement of the rockers the rollers

28 will roll along the ramp trackways 44 also lifting the ramp with respect to the axles 30, such lift and longitudinal movement being permitted by the slots 32. In this manner the rockers rock on their tracks 14 and the rollers 28 roll on their tracks 44 to the position shown in Fig. 4. In this manner a high lift is obtained without sacrificing the advantages of increased resistance obtained by the use of the rockers 10 and as fully explained in my Patent 2,374,155. As soon as the doors have been closed the ramp device will immediately return to the down position as shown in Fig. 1, thereby permitting locomotives or cars with closed doors to freely pass thereover. Separation of the door engaging member and base member is prevented by the axles or pins 22 and 30 passing through the rockers and through the sides of the base member or ramp member respectively.

While the invention has been described more or less in detail with specific reference to the drawings, it will be obvious that various modifications and rearrangements of parts other than those shown and described may be made and all such modifications and rearrangements of parts are contemplated as fall within the scope of the following claims defining my invention.

What is claimed is:

1. In a door closing device, a base member, a door engaging ramp member having a substantially horizontal flat top and depending side flanges, rollers movably connected to said base member, said connections including axles extending through said rollers and through elongated slots in said depending side flanges, and means having surfaces inclined to said flat top and supporting said ramp member on said rollers, said inclined surfaces moving along said rollers during longitudinal movement of the ramp member thereby raising the same relative to the base member.

2. In a door closing device, a base member, upwardly and forwardly inclined surfaces formed on said base member, rockers resting on said inclined surfaces for rocking movement relative thereto, rollers carried by said rockers remote from the rocking surfaces thereof, a door engaging ramp positioned above said base member, and downwardly and rearwardly inclined surfaces formed on said door engaging ramp and movably supported on said rollers during longitudinal movement of said ramp.

3. In a door closing device, a base member, upwardly and forwardly inclined surfaces formed on said base member, rockers resting on said inclined surfaces for rocking movement relative thereto, rollers carried by said rockers remote from the rocking surfaces thereof, a door engaging ramp positioned above said base member, downwardly and rearwardly inclined surfaces formed on said door engaging ramp and supporting the same on said rollers, means connecting said door engaging ramp and rollers for relative longitudinal movement, and additional means connecting said rockers and base member to limit the rocking movement therebetween.

4. In a door closing device, a base member, upwardly and forwardly inclined surfaces formed on said base member, rockers resting on said inclined surfaces for rocking movement relative thereto, rollers carried by said rockers remote from the rocking surfaces thereof, a door engaging ramp positioned above said base member, downwardly and rearwardly inclined surfaces formed on said door engaging ramp and sup-

porting the same on said rollers, and pin and slot connections between said door engaging ramp and said rollers and between said rockers and said base member.

5. In a device for closing a car door, a base member, trackways formed on said base member, a door engaging ramp positioned above said base member, trackways formed on said door engaging ramp, and interconnected rocker and roller devices supporting said ramp, said rockers being movable along said trackways on said base member and said rollers being movable along the trackways on said ramp to cause vertical and longitudinal movement of the ramp while engaged by the door in passing over the ramp.

6. In a door closing device, a base member, trackways formed on said base member, a door engaging ramp positioned above said base member, trackways formed on said door engaging ramp, substantially cylindrically curved rockers bearing on one of said trackways and rockable thereon, and rollers pivotally mounted on said rockers adjacent the center curvature thereof and bearing on the other of said trackways and rollable therealong, said rockers and rollers together supporting said ramp on said base member.

7. In a door closing device, a base member, a trackway formed on said base member, a door engaging ramp positioned above said base member, a trackway formed on said door engaging ramp, a substantially cylindrically curved rocker bearing on the trackway of the base member and rockable thereon, an axle extending from said rocker substantially in alignment with the center of curvature of the rocker, and a roller rotatably mounted on said axle and rollable on the trackway of the door engaging ramp.

8. In a door closing device, a base member, a trackway formed on said base member, a door engaging ramp positioned above said base member, a trackway formed on said door engaging ramp, a substantially cylindrically curved rocker bearing on the trackway of the base member and rockable thereon, an axle extending from said rocker substantially in alignment with the center of curvature of the rocker, and a roller rotatably mounted on said axle and bearing on the trackway of the door engaging ramp, said axle extending through a slotted portion of the door engaging ramp whereby the ramp is connected to said rocker but may have longitudinal movement relative thereto.

9. In a door closing device, a base member, a door engaging ramp member spaced above said base member, a rocker member movably bearing on said base member, and a roller member movably bearing on said ramp member and connected to said rocker member and movable therewith, said rocker and roller together supporting said ramp member on said base member for longitudinal and vertical movement relative thereto.
